UNITED STATES PATENT OFFICE

RICHARD M. WATSON, OF DETROIT, MICHIGAN

LOOSE-LEAF BINDER

Application filed July 11, 1925. Serial No. 42,882.

This invention relates to loose leaf binders. and has for its object a loose leaf binder that reaches almost the minimum in cost of construction, yet which provides an efficient, attractive binder.

5 Loose leaf binders of a very simple construction are now manufactured and are sold by the 5 and 10-cent stores. These binders usually comprise a single-crease folder with 10 grommeted perforations through which are threaded rings which may be opened or closed. These rings therefore project through the outside of the folder on either side and consequently always lie on the table, thus calculated to injure the finish.

It is the object of the present invention to provide a much improved construction of binder which can be used with the single-crease folder. The single-crease folder is 20 employed only in the cheapest loose leaf books for the reason that it eliminates the two-fold construction, which almost necessarily requires the use of a fabric to strengthen the creases. This fabric adds relatively large expense, proportional to the cost of the binder. Consequently it is not used in the very cheapest binders which are intended for sale in the 25 5 and 10-cent stores. It is the object of the present invention to provide an improved 30 construction of this type.

Referring to the drawings:

Fig. 1 is a perspective view of one form of the invention before the leaves are inserted.

Fig. 2 is a perspective view of the same 35 with the leaves inserted.

Fig. 3 is a fragmentary plan view of one end of the base plate, the ring being shown in section.

Fig. 4 is a cross section through the binder 40 when the same is closed.

Figs. 5 and 6 are perspective views of another form of the invention.

Fig. 7 is a section on the line 7—7 of Fig. 5.

Fig. 8 is a fragmentary cross section of the 45 same.

a designates a folder which is made of heavy paper, fibre board, straw board, pulp board, or similar material. It has one crease *b*. This folder has a pair of slots *c—c* in 50 one leaf. Immediately opposite these slots

on the other leaf is riveted a base strip of metal *e*, which supports a pair of paper-retaining rings *f*. The metal strip is transversely corrugated to support these rings, which may be welded to the corrugation or 55 tied thereto by striking in the metal as at *g*, Fig. 3.

These rings are permanent rings which do not separate but which are provided with slightly spaced ends at *h*, which permits the 60 insertion of the leaves as is shown in Fig. 2. When the other leaf of the folder is turned over to the closed position as shown in Fig. 4, the slots *c* pass over the tops of the rings and consequently the two leaves of the folder 65 can close upon the paper. Obviously when the book is closed the paper is kept away from the entering slots *h* of the ring so there is no possibility of the escape of the paper, hence the cover construction co-operates with this 70 type of ring in preventing the escape of the leaves.

Another form of the invention is shown in Figs. 5 to 8, inclusive. Here a slightly different base strip is employed, and is provided with a turned-over bead or socket *j* at one edge, which forms a journal bearing for the rod portion *k* which connects the two rings *m*. These rings can rock open or shut. As is shown in Figs. 5 and 6, there is a slight 75 friction where the ends of the rings pass down into the notch *n* in the end of the corrugation. This is indicated in Fig. 8. This slight friction serves to retain the rings in closed position under ordinary circumstances. Here again, in this form, the one leaf is slotted as 80 at *c—c*, so that the one cover leaf may be turned over toward the other cover leaf.

It will be apparent from this construction 85 that a loose leaf binder of a more efficient and better character is provided for the single-crease folder. This binder not only stiffens the back, but inasmuch as the rings protrude only through the top of the binder they are 90 not calculated to scratch the surface of the table, desk or other article of furniture.

Another important feature of this construction is that when the binder is open and in use it lies flat on the desk.

What I claim is:

1. A loose leaf binder, comprising a foldable cover and a base plate positioned adjacent the point of folding, the edge of said plate remote from said point of folding, being provided with a bossed-up bearing receiving a spindle of a prong element having a plurality of prongs for holding the leaves, and a plurality of bossed-up beads extending transversely of said base plate and provided with openings for receiving said prongs, said cover being provided with openings cooperating with said prongs and transverse beads.
2. A loose leaf binder, comprising in combination a folder formed of a single piece of material and provided with a crease to permit folding, a plurality of openings in one sheet of said folder adjacent said crease, a flat base plate secured to the other sheet adjacent the other side of said crease, said base plate being provided with paper holding rings, a bead formed along one edge of said base plate opposite the crease for forming a general bearing for the ring members and struck-up portions extending transversely of said base plate and provided with openings for receiving the open ends of said paper retaining rings, said rings and transverse struck-up portions cooperating with said openings.

In testimony whereof I have affixed my signature.

RICHARD M. WATSON.
